Primary Examiner — Kendra Leslie Hamilton(74) *Attorney, Agent, or Firm* — Suzanne Kikel(57) **CLAIM**

The ornamental design for a dog leash handle, as shown and described.

DESCRIPTION

FIG. 1 is a front perspective view of a dog leash handle, showing my new design in a condition for use.

FIG. 2 is a front elevational view of the dog leash handle of FIG. 1.

FIG. 3 is a rear elevational view thereof.

FIG. 4 is a right side view thereof.

FIG. 5 is a left side view thereof.

FIG. 6 is a top plan view thereof; and,

FIG. 7 is a bottom plan view thereof.

The broken lines showing of emergency buttons, clip and dog leash in FIG. 1 form no part of the claimed design.
